POINTER FOR A GAME BOARD OR
SIMILAR ARTICLE

Jacob B. Burke, 6771 Yellowstone Blvd.,
Forest Hills, N.Y. 11375

Filed Feb. 19, 1971, Ser. No. 117,224

Term of patent 14 years

Int. Cl. D21—01

U.S. Cl. D34—5

FIG. 1.

FIG. 3.

FIG. 4.

FIG. 2.

FIG. 5.

FIG. 6.

FIG. 8.

FIG. 7.

FIG. 9.

FIG. 1 is a top perspective view of a pointer for a game board or similar article.

FIG. 2 is a top plan view of the pointer.

FIG. 3 is a side view taken on line 3-3 of FIG. 2.

FIG. 4 is a cross sectional view taken on line 4-4 of FIG. 2.

FIG. 5 is a bottom plan view of the pointer.

FIG. 6 is a top plan view of another embodiment of the pointer wherein a smooth top surface is employed.

FIG. 7 is a cross sectional view taken on line 7-7 of FIG. 6.

FIG. 8 is a top plan view of a third embodiment wherein the bottom is rounded and the thumb and finger portions are more elongated.

FIG. 9 is an edgewise elevational view taken on line 9-9 of FIG. 8.

I claim:

The ornamental design for a pointer for a game board or similar article, as shown and described.
